**CHARGING-HOLE-COVER LIFTING-DEVICE
FOR COKE OVEN BATTERIES**
Günther Brandenbusch, Essen-Steele, Germany, assignor,
by mesne assignments, to Koppers Company, Inc.,
Pittsburgh, Pa., a corporation of Delaware
Filed Aug. 12, 1963, Ser. No. 301,245
4 Claims. (Cl. 214—658)

The invention relates to an electromagnetic charging-hole-cover lifting-device for coke oven batteries with a telescopically constructed lifting rod and a drive means capable of turning the cover in the frame of the charging hole.

The metallic charging-hole covers of coke oven batteries have a convex surface and are located in conical charging-hole frames with which they form a direct seal. This seal may be additionally supported by introduction of a sealing medium, such as powdered coal or coke, in a free annular space between the cover and frame above the metallic seal. The cover is turned once upon replacing it in the vicinity of the metallic sealing surface to eliminate the deposits which are formed by the sealing medium and by formation of condensate from the distillation gases of the oven chamber.

It is now necessary to insert the cover concentrically and to turn it for production of a satisfactory seal. An accurate concentric placing of electromagnets on the covers is not always immediately possible with the previously known electromagnetic cover lifting device. In the case of off-center seating an eccentric motion of the cover occurs, resulting in damage to the sealing surfaces and the frame in the masonry is loosened under certain circumstances.

This invention comprises connecting the lower end of the lifting rod to a lifting magnet by means of centering pins having a cross-section projecting through centering openings having a larger cross-section, for example a plate fastened on the lifting rod; arranging the centering pins on the lifting magnet; and adjusting them in the position effecting a concentric turning of the charging-hole cover.

An inclined position of the charging hole cover is prevented in each case by means of such a centering device because the centering pins provided with rollers are preferably moved along the wall of the centering openings and into the centering position.

According to the invention the centering pins and the lifting magnet are supported on balls or rollers suitably supported by the lifting rod, so that as little friction as possible has to be surmounted for the movement of the centering pins to the centering position.

Another feature of the invention is that the lifting rods are turned by a common drive means arranged on the charging car.

Also, according to the invention, the upper telescope section that is not capable of being raised is provided with slip rings to which the cables from the lifting magnet are connected. In this way, it is possible to place the cables inside the telescopic pipe so that they are protected from damage.

The invention is illustrated by way of example in the drawings.

FIGURE 1 is a vertical section through one of the lifting devices for a charging hole cover.

FIGURE 2 is a section along line II—II of FIG. 1, and

FIG. 3 is a sectional view along line III—III of FIG. 1.

Charging holes 2 are arranged in the oven deck 1 of the oven battery for charging coal into the oven chambers; the charging holes are located behind one another in the

line of sight for one oven chamber. Charging holes 2 are provided at the top with conical, metallic charging-hole frames 3, in which metallic charging-hole covers 4 are inserted.

5 The lifting of the charging-hole covers 4 is effected by means of electro lifting magnet 5. The electric lifting magnet 5 is provided with a supporting ring 6. A supporting plate 7 which is provided with rollers 9 supported by centering pins 8 is firmly fastened to the upper end of the supporting ring 6.

The supporting plate 7 rests on balls 10 which are mounted on a supporting plate 11 which is firmly connected with lifting rod 12 by a concentric ring 13 and a plate 14.

15 Furthermore, a centering plate 15 which is provided with centering openings 17 concentrically arranged around the vertical axis is mounted on connecting ring 13.

Terminal switches 18 are connected with the lifting magnet and give a signal by contacts (not illustrated) 20 when the lifting magnet is placed on the charging hole cover 4. Cable 19 is connected to lifting magnet 5 and terminal switches 18. The cable passes through the lifting rod 12 consisting of a pipe.

The lifting rod 12 is constructed telescopically and a 25 lower pipe 12a can be moved inside an upper pipe 12b. Both pipe sections are designed so that they do not turn in relation to one another, for example by use of a key and keyway 20 or many-sided cross-sectional forms.

The lower telescopic pipe 12a is raised and lowered 30 by means of a lever 21 preferably a common lever for the lifting rods of all charging hole covers, with interposition of a shaft 22. The one end of lever 21 engages in a bushing 23 firmly connected with the lower telescopic pipe 12a and is moved vertically by means of an electro 35 control means or a piston motor 24. The lower telescopic pipe 12a is guided in bearings 25 and is capable of being moved inside the upper telescopic pipe 12b.

The telescopic pipe 12b is firmly connected with a stub 40 shaft 27 which is rotatably mounted in a bearing 28. Stub shaft 27 is driven by means of a bevel gear 29 and a shaft 30 which is common for all drives of the individual lifting rods 12. The cable 19 of the lifting magnet 5 and terminal switch 18 are connected with slip rings 31 which are separately arranged around the upper telescopic pipe 12b and to which current is supplied through lines 32.

45 In the case of any eccentric placing of the lifting magnet 5 on the charging-hole cover 4, as illustrated by broken lines, a lifting of the charging-hole cover 4 is immediately possible without turning the same in the charging-hole frame 3 of the centering device. However, if cover 4 is turned, for example in the direction of arrow 34 in FIGURE 2, upon lifting or in any case upon inserting, the centering pins 8 together with their rollers 9 arrive at the edges of the centering openings 17 as indicated in dotted lines, whereby the cover 4 is induced with lifting magnet 5 to make an eccentric motion upon turning the lifting rod. As soon as the cover 4 enters the 50 area of the charging hole frame 3, the rollers 9 will be forced, by movement along the walls of the centering openings 17, to produce a concentric rotation of the cover 4 by means of the eccentric lifting magnet which rests on the cover 4. That is to say, when the cover 4, which 55 is eccentric with respect to the magnet 5, is started into the charging hole frame 3, the group of elements including the cover, the magnet 5, the supporting rings 6, and the supporting plate 7, is movable on the ball rollers 10 to effect a centering of the cover 4 in the charging hole frame 3, under the action of the rollers 9 working against the walls of the centering openings 17.

I claim:

1. Apparatus for handling coke oven charging hole
vers comprising:
  - (a) a support member which is rotatable about an axis;
  - (b) spaced apart first and second planar members fixed transversely across said support member with said second planar member having therein an axial aperture comprised of a plurality of lobate-centering openings arranged concentrically around and communicating with a central opening;
  - (c) a plurality of bearings mounted on said first planar member;
  - (d) a magnet for lifting and handling said cover;
  - (e) a third planar member fixed to said magnet and disposed intermediate said first and second planar members and movably supported on said bearings; and
  - (f) a plurality of guide roller members mounted on said third planar member, each roller member operating in its respective lobate centering opening, said lobate centering openings having a cross section area greater than the cross sectional area of said roller members, whereby when said cover is rotated about its axis said roller members engage the wall of their respective lobate centering opening and move in a generally circular path and said cover is centered with respect to said charging hole.
2. Apparatus for handling coke oven charging hole
vers comprising:
  - (a) longitudinally telescopicable rods which are inter-engageable for simultaneous rotation about a common axis;
  - (b) spaced apart first and second planar members fixed transversely across said rods with said second planar member having therein an axial aperture comprised of a plurality of lobate-centering openings arranged concentrically around and communicating with a central opening;
  - (c) a plurality of bearings mounted on said first planar member;
  - (d) a magnet for lifting and handling said cover;
  - (e) a third planar member fixed to said magnet and disposed intermediate said first and second planar members and movably supported on said bearings;
  - (f) means to reciprocate said rods;
  - (g) means to rotate said rods about said axis; and

- (h) a plurality of guide roller members mounted on said third planar member, each roller member operating in its respective lobate centering opening, said lobate centering openings having a cross section area greater than the cross sectional area of said roller members, whereby when said cover is rotated about its axis said roller members engage the wall of their respective lobate centering opening and move in a generally circular path and said cover is centered with respect to said charging hole.
3. The invention set forth in claim 2 wherein:
  - (a) means is provided to energize and deenergize said magnet.
4. Apparatus for handling coke oven charging hole covers comprising:
  - (a) longitudinally telescopicable rods which are inter-engageable for simultaneous rotation about a common axis;
  - (b) spaced apart first and second planar members fixed transversely across said rods with said second planar member having therein a plurality of circular centering openings arranged concentrically around a point in said second planar member;
  - (c) a magnet for handling said cover;
  - (d) a third planar member fixed to said magnet;
  - (e) means for movably supporting said third planar member intermediate said first and second planar members;
  - (f) means to reciprocate said rods;
  - (g) means to rotate said rods about said axis; and
  - (h) a plurality of guide roller members mounted on said third planar member and operating in respective circular centering openings having a cross sectional area greater than the cross sectional area of said roller members whereby when said rods are rotated about said axis said roller members engage the wall of their respective centering opening and move in a generally circular path and said cover is centered with respect to said charging hole.
